UNITED STATES PATENT OFFICE.

WILLIAM A. DOREY, OF NEWARK, OHIO, ASSIGNOR TO HOLOPHANE GLASS COMPANY, INC., OF NEW YORK, N. Y., A CORPORATION OF NEW JERSEY.

DESIGN FOR A REFLECTOR.

Application filed May 6, 1921. Serial No. 467,290. Term of patent 14 years.

To all whom it may concern:

Be it known that I, WILLIAM A. DOREY, a citizen of the United States, residing at Newark, in the county of Licking and State of Ohio, have invented a new, original, and ornamental Design for Reflector, of which the following is a specification, reference being had to the accompanying drawing, forming a part thereof.

Fig. 1 is a side elevation of the reflector made according to my design.

Fig. 2 is a front elevation.

Fig. 3 is a top plan view.

The reflector is characterized by having the plane of its lower or open end *a* oblique to its axis *b* to thereby provide one side *c* shorter than the opposite side *d*, and by having the side *c* of the reflector nearer its axis and of conical configuration as indicated at *e*.

I claim:

The design for a reflector as shown and described.

WILLIAM A. DOREY.
